UNITED STATES PATENT OFFICE.

FRANK B. FLOWER, OF PHILADELPHIA, PENNSYLVANIA.

CANOE-BARROW.

1,109,520.

Specification of Letters Patent.

Patented Sept. 1, 1914.

Application filed January 14, 1914. Serial No. 812,165.

To all whom it may concern:

Be it known that I, FRANK B. FLOWER, a citizen of the United States, residing at Philadelphia, in the county of Philadelphia and State of Pennsylvania, have invented new and useful Improvements in Canoe-Barrows, of which the following is a specification.

This invention relates to a canoe barrow which is adapted to be connected detachably with one end of a canoe and has a supporting wheel adapted to be used in rolling the same along a floor or other supporting surface.

Heretofore it has been necessary, in moving a canoe from the storing rack to the water's edge, to carry the same bodily. When the canoe was empty it could be inverted and carried overhead by one person, but when it was loaded it required two persons to carry the same, each grasping the canoe at one of its ends during this operation. It is oftentimes desirable or even necessary that a person shall carry his boat without help from any one else. In order to do this, it is necessary to empty the boat and lift the same above the head, or slide the boat along the ground or dock, either of which proving inconvenient, and the latter particularly hazardous to the bottom of the boat.

It is therefore the purpose of my invention to provide a light and yet strong wheeling device, or "barrow" as it may be termed, which is adapted to be connected readily with one end of the canoe so that one person may lift the other end of the same and wheel it along the supporting surface to or from the water's edge with a minimum amount of labor or inconvenience.

A further object of the invention is to provide a device of this character which is constructed simple and is composed of few parts which may be cheaply manufactured and are combined in such a manner that the device may be attached readily to a canoe and will support the same effectively without injuring the canvas of the same, it being engaged with the keel and gunwales alone.

The invention consists in the features of construction, combination, and arrangement of parts, hereinafter fully described and claimed, reference being had to the accompanying drawing, in which:

Figure 1 is a side elevation of the device

in use upon a canoe, the latter being broken away; Fig. 2 is a top plan view of the same; Fig. 3 is a transverse sectional view taken therethrough; and, Fig. 4 is a perspective view of the barrow alone.

In the drawing, the numeral 1 designates the body of the barrow which is constructed preferably of a strip of metal or some other suitable material which is bent so as to provide a narrowly spaced, substantially U-shaped portion 2 between which a supporting wheel 3 is mounted upon the axle 4, which latter is secured to the parallel sides of this portion of the body by means of the nuts 5 which are threaded onto the ends of the axle. The upper ends of the strip from which the body is constructed, are bulged laterally as at 6 to provide canoe-embracing arms which conform in contour to the sides of the canoe but are not intended to engage the same, except at their upper ends, which have inward, gunwale-engaging projections 7. The arms 6 are also inclined upwardly from the U-shaped portion 2 so that the end of a canoe, such as is indicated by the numeral 8 in Figs. 1 to 3 of the drawing, may be inserted between the said arms without turning the portion 2 into such an angle to the horizontal that its cross portion 9 will become engaged with the supporting surface over which the wheel is adapted to pass. The extremities of these arms 6 are also bent upwardly to a slight extent so as to bring the flat projections 7 into such angular relation to the arms that they will bear evenly against the upper face of the gunwale.

A transverse chain 10 or the like extends between the sides of the U-shaped portion 2 of the body inwardly with respect to the wheel 3 and is adapted to support the keel of the canoe when the device is applied thereto. The opposite ends of this chain are adapted to be engaged within the openings 11 provided in the sides of the body portion 2, there being a plurality of these openings in each side of the said body portion, which are longitudinally spaced and are disposed in alignment with the respective openings in the other side, so that the chain may be adjusted upon the body to accommodate the device to the particular canoe with which it is to be used.

When it is desired to transport the canoe from place to place, the barrow is applied to one end of the canoe so as to mount the same

upon the supporting wheel, whereupon the opposite end of the boat may be grasped and lifted to a convenient height for wheeling the boat along the ground or other supporting surface. This operation may be performed as should be readily understood by one person with ease and without danger of scarring or otherwise injuring the canvas-covered body of the canoe.

10 What is claimed is:

1. In a device of the class described, the combination with a boat, of a transporting barrow therefor comprising a body, a supporting wheel rotatably mounted upon the body, a supporting member provided upon said body for engagement with the keel of the boat, a pair of arms provided upon the said body and being adapted to embrace the sides of the boat, and an inwardly projecting extension provided terminally upon each of said arms for engagement with the upper face of the gunwale.

2. In a device of the class described, the combination with a boat, of a transporting barrow therefor comprising a body, a supporting wheel rotatably mounted upon the body, a supporting member provided upon said body for engagement with the keel of the boat, a pair of arms provided upon the said body and being adapted to embrace the sides of the boat, and an inwardly projecting extension provided terminally upon each of said arms for engagement with the upper face of the gunwale, each extension having its inner end bent angularly for engagement with the inner face of the gunwale.

3. In a device of the class described, the combination with a boat, of a transporting barrow therefor comprising a substantially U-shaped body providing arms adapted to embrace the sides of the boat, a supporting wheel rotatably connected with the body adjacent to the cross portion thereof, a keel-supporting member mounted between the arms of the body in spaced relation to the free ends of the same, and inwardly projecting extensions formed upon the free ends of the arm for engagement with the upper

faces of the gunwales, the said arms being bent between the keel-supporting member and the supporting wheel to arrange the lower portion of the body at an oblique angle to the longitudinal axis of the boat when in applied position.

4. In a device of the class described, the combination with a boat, of a transporting barrow therefor comprising a substantially U-shaped body providing arms adapted to embrace the sides of the boat, a supporting wheel rotatably connected with the body adjacent to the cross portion thereof, a keel-supporting member mounted between the arms of the body in spaced relation to the free ends of the same, and inwardly projecting extensions formed upon the free ends of the arm for engagement with the upper faces of the gunwales, the keel-supporting member being longitudinally adjustable upon the body.

5. In a device of the class described, the combination with a boat, of a transporting barrow therefor comprising a substantially U-shaped body providing arms adapted to embrace the sides of the boat, a supporting wheel rotatably connected with the body adjacent to the cross portion thereof, a keel-supporting member mounted between the arms of the body in spaced relation to the free ends of the same, and inwardly projecting extensions formed upon the free ends of the arm for engagement with the upper faces of the gunwales, the arms of the body being provided with a plurality of longitudinally spaced openings arranged in transversely alining sets and the keel-supporting member being in the form of a flexible member having hooks provided terminally for detachable engagement within the arm openings.

In testimony whereof I affix my signature in presence of two witnesses.

FRANK B. FLOWER.
